UNITED STATES PATENT OFFICE

2,094,435

DOUBLE WINDOW CONSTRUCTION

Edward F. Toney, Pittsburgh, Pa., assignor to
 Pittsburgh Plate Glass Company, Allegheny
 County, Pa., a corporation of Pennsylvania

Application September 6, 1935, Serial No. 39,424

3 Claims. (Cl. 20—56.5)

The invention relates to a double glazed window and has for its objects the provision of an improved mounting for the two sheets of glass, which is relatively cheap and simple; which is 5 secure and permanent; which provides for an adequate seal; and which can be used with glass and spacers which have varying thickness. Certain embodiments of the invention are illustrated in the accompanying drawing, wherein:

10 Figure 1 is a section through one edge of the unit as assembled preliminary to clamping the two members constituting the channel together. Fig. 2 is a section similar to that of Fig. 1, but with the parts of the channel clamped together 15 and with the unit mounted in a car frame. And Fig. 3 is a section similar to that of Fig. 1, but with the unit mounted in a wood sash.

Referring to Figs. 1 and 2, 3 and 4 are glass sheets and 5 is a spacer preferably of rubber 20 or other resilient material capable of forming a seal and lying between the sheets at the margins thereof. The frame which carries the sheets is of channel form and comprises the outside member 6 and the inside member 7. There are four 25 of each of these members to correspond to the four sides of the window and after assembly, they are secured together at the corners by welding, soldering or by interlocking mechanical means well known in the art.

30 The member 6 is of L cross section and comprises a flange 8 in opposition to the face of the sheet 3 and a base 9 extending across the edges of the two sheets with its end 10 projecting past the face of the sheet 4, as illustrated. The member 7 is also of L shape having a flange 11 in opposition to the face of the sheet 4 and a base 12 of hook shape formed, as indicated in 35 Fig. 1, the opposing faces of the parts 10 and 11 being preferably serrated to guard against slipping after the part is bent to clamping position. The members are preferably of extruded metal, such as aluminum or brass, and are relatively 40 free from temper so that the part 7 will remain in any position to which it is bent.

45 Packing and sealing material 13 and 14 is interposed between the outer faces of the glass sheets and the flanges 8 and 11. After the parts are positioned, as indicated in Fig. 1, pressure is applied to cause a movement of approach between the flanges 8 and 11, thus compressing the spacer 5 and the sealing strips 13 and 14, after which the flange 12 is bent by a suitable 50 press into clamping engagement with the end 10 of the flange 9. This completes the operation 55 of assembling the unit, aside from the securing

of the four members 6 and the four members 7 together at the corners of the windows, as hereinafter referred to.

The unit may now be mounted in a sash or frame, either of wood or metal in any suitable 5 manner. In Fig. 2 the mounting is in a car frame, 14 and 15 being the side plates of the frame and 16 being clamping strips secured by the screws 17. Packing means 18 of rubber or the like is preferably used, as shown. 10

Fig. 3 illustrates the mounting of the unit in a wood sash 19, the putty 20 and nail 21 extending through suitable perforations in the members 6 and 7 serving to secure the unit in place. 15 When replacements are required, the unit is removed from its frame, and the mounting is removed by opening the flange 12 with a suitable tool. The mounting is relatively cheap and permanent and permits of a substantial degree of adjustment to accommodate glass and spacers 20 of varying thickness.

What I claim is:

1. In a double window construction, a pair of spaced glass sheets with spacing and sealing means between their margins, a channel in which the edges of the glass sheets are mounted comprising an L-shaped member having its base extending across the edges of the sheets and projecting past the outer face of one sheet and having its flange in opposition to the outer face 30 of the glass sheets, and a second member having a flange in opposition to the outer face of the other glass sheet and also having a hook-shaped base at right angles to the flange which fits around and clampingly engages the edge of 35 the base of the L-shaped member, said members having means integral therewith to prevent lateral displacement of the members.

2. In a double window construction, a pair of spaced glass sheets with spacing and sealing 40 means between their margins, a channel in which the edges of the glass sheets are mounted comprising an L-shaped member having its base extending across the edges of the sheets and projecting past the outer face of one sheet and 45 having its flange in opposition to the outer face of one of the glass sheets, and a second member having a flange in opposition to the outer face of the other glass sheet and also having a hook-shaped base at right angles to the flange which 50 fits around and clampingly engages the edge of the base of the L-shaped member, the interengaging surfaces of the two members being provided with serrations.

3. In a double window construction, a pair 55

5 of spaced glass sheets with spacing and sealing means between their margins, a channel in which the edges of the glass sheets are mounted comprising an L-shaped member having its base extending across the edges of the sheets and projecting past the outer face of one sheet and having its flange in opposition to the outer face of one of the glass sheets, and a second member

free from temper having a flange in opposition to the outer face of the other glass sheet and also having a base of U shape, whose sides lie on opposite sides of the base of the L-shaped member and clampingly engage the same, both engaging surfaces being provided with means integral therewith for insuring the clamping engagement.

EDWARD F. TONEY.
